AUXILIARY BELT SHIFTING DEVICE

Michael Wachsman, Brooklyn, N. Y.

Application May 16, 1946, Serial No. 670,093

1 Claim. (Cl. 74—242)

1

The object of this invention is to provide a device adapted to be mounted upon a belt shifting mechanism to serve as an auxiliary power means for moving the shipping lever from driving to idle position, i. e. to shift the belt from the tight to the loose pulley.

The device is intended for use on belt shifting mechanisms in which the shipping lever is moved manually into driving position and temporarily locked in such position during normal driving conditions. The shipping lever is however, automatically released and moved into idle position when the normal driving operation of the machine is interrupted, for example when a break occurs in some moving part.

The means for moving the shipping lever into idle position must be forceful and instantaneously operable when occasion arises. Usually a spring is employed for this purpose. It has been found, particularly in the case of knitting machines, that because of unavoidable space limitations, such shipping lever spring which it is possible to install and use must be relatively small and therefore limited in power and durability. Such springs wear out rather quickly or become too weak to move the lever quickly or not at all.

The device herein disclosed provides an auxiliary additional spring power means for instantaneously and forcefully moving the shipping lever into idle position after it has been released from the control mechanism. The spring acts by expansion and therefore lasts longer and acts quicker. In the accompanying drawing illustrating the invention

Fig. 1 is a side view of the device.

Fig. 2 is an end view looking from the left in Figure 1.

Fig. 3 is a vertical sectional view.

Fig. 4 is a diagrammatic illustration showing the device attached to the belt shifting mechanism of a knitting machine.

Fig. 5 is a diagram of a control mechanism of a knitting machine.

The device comprises a cylinder 10 held in a support 11 in axially adjustable relation by set screws 12. The rear end of the cylinder is closed by a plug 13. The forward end 14 is open. Within the cylinder there is placed a powerful expansion coiled spring 15 which carries a rear plug 16 and a forward plug 17. A space regulating screw 18 is threaded into the plug 13 as shown. The support 11 is in the form of a relatively strong rigid casting forming an upright arm 19 which receives the cylinder 10 and 55

2

also forming a bracket portion 20 provided with screw holes 21.

In use the device will be mounted with the cylinder 10 and spring 15 in axial alignment with the shipping lever of a knitting or other machine, the forward plug 17 in the spring touching the free end of the shipping lever when the latter is in idle position, the spring 15 being wholly expanded. When now the shipping lever 10 is moved into driving position, the spring 15 will be compressed within the cylinder and power will be stored in the spring ready for expansion when the shipping lever is released.

When for any reason the shipping lever is released, the spring 15 will suddenly expand so that the forward plug 17 will be shot out from the cylinder and push the shipping lever into idle position. This will happen regardless of the action of the regular shipping lever spring. When 20 the shipping lever is again moved into driving position, the spring 15 is again compressed and ready to act.

The power of the spring 15 is adjustable by the regulating screw 18 which regulates the space 25 within which the spring may be compressed. In addition, the entire cylinder and spring are adjustable lengthwise in the arm 19 of the support 11. Should it be found that the power of the spring 15 is greater than required, the cylinder 30 10 may be moved further rearwards, to the right in the drawing. By moving the cylinder forward in the support 11 the compression of the spring is increased, as will be understood.

Figs. 4 and 5 illustrate diagrammatically and 35 by way of example the installation and operation of the device when used on a knitting machine. In Fig. 4 the numeral 25 indicates the driving shaft of a knitting machine with the tight and loose pulleys 26, 27, respectively. The belt is marked 28 and is shown driving the tight pulley. The belt shifter 29 is carried by the slidably mounted shipping lever 30, the latter having been moved manually from idle to driving position by a well known form of cam mechanism indicated at 31 and operated from a handle 32 through a train of gears as shown. A spring 33 acts to pull the shipping lever from driving to idle position. As stated above, it has been found that springs as 33 are too weak to function for any length of time and frequently break.

The shipping lever is held in driving position by a control mechanism such as illustrated in Fig. 5. The auxiliary device is secured to the control box 34 by bolt 35 passing through the

holes 21 in the support 11. These holes are drilled to match certain holes in the box which exist for other purposes but which may be used for attaching the auxiliary device. The cylinder 10 with the spring 15 are alined with the shipping lever through a hole 36 in the control box.

A simple form of control mechanism is shown diagrammatically in Fig. 5. For example, the shipping lever 30 may have a lug 40 which is positioned behind the armature lever 41 of an electromagnet 42 when the lever is pushed into driving position. In a knitting machine, for example, the magnet is connected via a battery 43 to a thread detector 44 which rests upon a travelling thread 45. When the thread breaks, the detector falls down upon a contact 46 to close the electric circuit of the machine. The armature lever is then withdrawn and the shipping lever released to be acted upon by the spring 15, or both springs if the regular spring 33 functions.

The control unit shown in Fig. 5 is a part of the unit shown in Fig. 4, but is illustrated separately for the sake of clearness. The shipping lever 30 is identified in both views. Normally during operation the armature lever 41 prevents the shipping lever 30 from shifting the belt to the loose pulley. When however, the electric circuit is closed as explained above, the armature lever 41 is moved away from the lug 40 and then the shipping lever is spring actuated to shift the belt to the loose pulley and the machine stops running. When the fault has been attended to, the operator operates the belt shifting mechanism to move the belt back to the tight pulley and the machine starts operating. When thus shifting the shipping lever back to running position the operator holds the armature lever 41 out of the path of movement of the lug 40 so the latter can by-pass the armature lever, or other means may be employed for this purpose, not shown.

The belt shifting mechanisms for knitting machines are made as compact as possible and the several parts of the mechanism are crowded together within a very small space. It is there-

fore impossible to reinforce the regular spring when it becomes weak, and frequent and difficult replacements are necessary. By the addition of the auxiliary device herein disclosed a material disadvantage in existing belt shifting mechanisms is overcome. The auxiliary device is not limited in use to knitting machines but may be found useful for other machines as well.

I claim:

10 A belt shifting mechanism comprising a housing, a shipping lever slidably mounted therein, means accessible from outside the housing for moving said lever into belt driving position, means for releasably locking the lever in said position, 15 a spring within the housing for automatically moving said lever into belt idling position after it has been released, an auxiliary power spring device for moving said shipping lever into belt idling position as aforesaid, said device comprising a support mounted on the outside of said housing, a spring cylinder secured in said support and extending into the housing in axial alignment with said shipping lever, a compressible spring in said cylinder, means in the latter for positioning the spring in contact with the shipping lever to be compressed by said lever when it is moved into belt driving position as aforesaid, said spring being free to expand to move the lever into said belt idling position 30 after said lever has been released as aforesaid, means for adjustably securing said cylinder in the said support, the said last named means and the said spring positioning means being accessible from outside the said housing.

MICHAEL WACHSMAN.
